Application August 17, 1956, Serial No. 604,798

5 Claims. (Cl. 200—48)

This invention relates to sectionalizing switches, and with regard to certain more specific features, to gang-operated, air-break switches of this class.

Among the several objects of the invention may be noted the provision of a reliable switch of the class described constructed to be mounted on a single pole and conveniently operated from a single location at the pole base, adapted to be set up for a wide selection of sectionalizing feeder and loop connections, each phase assembly of which comprises a compact side-break arrangement of switch parts radially organized to eliminate interference between swinging switch elements; the provision of a switch of the class described, the parts of which are arranged for maximum interchangeability so as to minimize the number of different structural elements required to assemble a complete switch; and the provision of a switch of the class described which may be conveniently made up either for three-way or two-way connections and for various directions of swing of its switch elements. Other objects and features will be in part apparent and in part pointed out hereinafter.

The invention accordingly comprises the elements and combinations of elements, features of construction, and arrangements of parts which will be exemplified in the structures hereinafter described, and the scope of which will be indicated in the following claims.

In the accompanying drawings, in which one of various possible embodiments of the invention is illustrated,

Fig. 1 is a front elevation of a pole showing a three-phase embodiment of our invention supported thereon, portions being broken away for compactness of illustration;

Fig. 2 is a horizontal section taken on line 2—2 of Fig. 1;

Fig. 3 is a vertical section taken on line 3—3 of Fig. 2;

Fig. 4 is an enlarged fragmentary vertical section taken on line 4—4 of Fig. 2;

Fig. 5 is a horizontal section taken on line 5—5 of Fig. 4;

Fig. 6 is a view similar to Fig. 5, but showing an alternative position of a certain cam ring;

Fig. 7 is a fragmentary angled vertical section taken on line 7—7 of Fig. 2, being enlarged to the scale of Fig. 4;

Fig. 8 is an enlarged section taken on line 8—8 of Fig. 7;

Fig. 9 is an enlarged fragmentary section taken on line 9—9 of Fig. 2; and,

Fig. 10 is a skeleton plan view illustrating certain structural principles, the solid lines indicating switch-closed positions and the dotted lines indicating switch-opened positions of certain side-break switches.

Corresponding reference characters indicate corresponding parts throughout the several views of the drawings.

Referring now more particularly to Fig. 1, there is shown at numeral 1 a conventional line pole adapted to support three switch sections for controlling a three-wire

2

or three-phase circuit 3. Each phase of the circuit is controlled by one of three identical assemblies A, B, C, one of which (A) will be described in detail below, thus serving to describe all of the assemblies A, B and C, the parts of each being indexed the same. It will be understood that each assembly may, if desired, be employed for single-phase operation, or two of them for two-phase operation.

Referring now to Figs. 2 and 3, assembly A is composed of a horizontal platform 5, built up by welding or equivalent fastening means to provide side members 7 joined at adjacent ends to a horizontal brace 9. The other ends of members 7 and 9 are joined by horizontal transverse braces 11 extending to brace 9. At the connection between braces 9 and 11 is located a short channel section 13 by means of which attachment is made to the pole. One attachment is constituted by a bolt 15 fastened through the pole and the other by means of a pair of straps 17 held by lag screws 18. Cross braces 19 connect the members 9 and 11, whereby a rigid horizontal platform results. Angled braces 21 are attached at their upper ends to the platform 5 and at their lower ends to a support 13, the latter being downwardly fastened to the pole 1. A stiffening auxiliary brace is shown at 25. Fastened to the corners of the triangular structure 5 are bars 27, forming anchors for strain insulators 29 which support wires 3. Jumpers leading from the wires are indicated at 31.

Extending from the transverse braces 11 are bearing plates 33, having bolt and slot connections 35 for position-adjusting purposes. These bearing plates carry bearings 37 for control shafts 39 and 41, respectively. These shafts extend through corresponding bearings 37 in all of the assemblies A, B, C, and downward to a point near the ground, and are adapted for manual control by an operator standing at the base of the pole 1. At their lower ends the shafts are carried rotatably in suitable pole brackets 43, being at this point provided with hinged operating handles 45. Operating positions of the handles are as suggested by the dotted line 45' at the left hand bottom of Fig. 1.

A third control shaft 47 traverses all of the assemblies A, B and C, passing through openings 49 in the supports 23. The shaft 47 also passes through braces 9 via bearing brackets 51, bolted to the braces as shown at 53. The lower end of the shaft 47 is supported in a rotary manner in another bracket 48 near the lower end of the pole 1, where it also is provided with another hinged operating handle 45. Adjacent each bearing bracket 51, the shaft 47 carries a control arm 55, and adjacent each bracket 37 the shafts 39 and 41 respectively carry arms 57 and 59.

Near the respective corners of the triangular structure formed by each horizontal platform 5 are rotary insulators 61, 63 and 65. Each of these insulators has a lower operating shaft 67 cemented into and extending from its lower end. To each shaft 67 is bolted an arm 69 and also a hollow gudgeon 71 which is rotary in a hollow bearing block 73. The latter in turn is bolted to the appropriate structural member of platform 5. For example, in Fig. 7 is illustrated the insulator 61 having the stated arrangement, wherein the bearing block 73 is carried on one of the transverse braces 11. Each bearing block 73 has bolted thereto a stop 75 engageable by a stop arm 77 extending downward from the respective arm 69, whereby rotation of the insulator is limited.

The stop member 75 is supported relative to member 11 by means of one of a plurality of holding bolts 76. The member 75 is slotted for effecting adjustments in the limitations upon the movement of member 77. Arm 69 may be variably positioned by resetting it relative to its fastening bolts 70, of which there are four, equally spaced.

Each arm 69 has pivoted thereto a clamp 79. The clamp 79 associated with insulator 61 is attached to a connecting rod 81, extending to a similar clamp 79 pivoted on arm 57. The clamp 79 associated with insulator 63 is attached to a connecting rod 85, extending to a similar clamp 79 pivoted on arm 59. The clamp 79 associated with insulator 65 is attached to a connecting rod 87, extending to a similar clamp 79 pivoted on arm 55.

Anticlockwise rotation of shaft 39 will cause anticlockwise rotation of insulator 61 up to a limiting point, as determined by its associated stops 75 and 77; clockwise rotation of shaft 41 will cause clockwise rotation of the insulator 63 to a limiting point as determined by its corresponding stops; and anticlockwise rotation of shaft 47 will cause anticlockwise rotation of insulator 65 up to a limiting point as determined by its corresponding stops. Shafts 39, 41 and 47 are rotatably controlled from the respective lower handles 45.

Attached to the upper end of each insulator 61, 63 and 65 (as illustrated, for example, in the case of insulator 61 in Fig. 7) is a cap 89 to which is pinned (as at 91) a threaded conductive shank 93. This forms part of a hollow conducting elbow 95, from which extends a tubular conducting switch arm 97, fastened thereto as illustrated at 99. Shank 93 is threaded through an internally threaded hollow conducting terminal plate 101. Washers 105 and a protective skirt 103 protect the rotary threaded connection from the weather and permit some axial movement between members 93 and 101. The terminal plate 101 carries wire connectors 107 for connecting an appropriate jumper 31. Rotation of each insulator as above described results in swinging of its arm 97 to perform a switching action, the stated threaded connections forming a conducting bearing with the respective terminal plates 101. In order to maintain good electrical threaded contact, the arrangement shown in Fig. 8 is used, wherein one side of the plate 101 is extended as a hollow cylinder 109 provided with an enclosing cap 111 forming a reactive backing for a compression spring 113. Spring 113 is operative upon a fiber or like disc 115 for applying side pressure on the threaded shank 93 relative to the plate 101. This assures pressurized thread engagement for reliable current conduction.

Geometrically the rotary insulators 61, 63 and 65 are on the corners of an equilateral triangle. At the approximate center of this triangle is a stationary insulator 117, the lower pintle 119 of which (Fig. 4) is fixedly attached to the brace 9 by a fixed spacing block 121, bolts 123 being used for the purpose.

Fastened to the upper end of the insulator 117 is a stationary conductive spider or bushing 125, held in place on insulator 117 by bolts 127. The spider 125 has attached to it marginally (see bolts 126 in Fig. 2) three identical conductor blocks 129, each of which has an internal threaded cylinder 131 (Fig. 4). These are for threadably receiving threaded conducting shanks 133 respectively of elbows 135, 136 or 138 (Fig. 2) to which socket-forming spring conductive clip assemblies 137 respectively are attached. Each block 129 is radially adjustable in position by reason of slots 128 for reception of the bolts 126. Clip assemblies 137 are adapted springingly to receive the outer ends 139 of switch arms 97.

Adequate conductive engagements between the threads 131 and 133 (Fig. 4) are obtained as follows: Below each shank 133, each block is made hollow, as shown at 141, and provided with a removable cover 143. From the threaded shank 133 extends a polygonal stub 145 for reversibly receiving the cooperatively notched inside of a cam ring 147. Each cam ring 147 has lugs 149 and 151 for receiving thrust from compression springs 153. Each ring 147 also has cam lift portions 155 for detent engagement with a ball end 156 of a detent 157. The detent is biased by means of a spring 159 in a pocket

member 161 which is threaded into the side of the block 129. Lug 151 also is engageable either with a lug 163 (Fig. 5) or a lug 165 (Fig. 6). By comparing Figs. 5 and 6, it will be seen that a cam ring, by reason of internal engaging notches 167, may be applied to a stub end 145 in either of two horizontal turned-over positions. It is applied in the Fig. 6 position on the lower end of the elbow 135 (Fig. 2) and in the Fig. 5 position to the lower ends of the elbows 136 and 138.

In view of the above, it will be seen that by rotating shafts 39 and 47 clockwise, i. e., by operating their respective handles 45, the insulators 61 and 65 will be rotated clockwise from the switch-closed positions shown in Figs. 2 and 10 to switch-open positions. Darts *a* indicate the direction of this movement. In accordance with such movement, the elbows 136 and 138 move anticlockwise to switch-open positions, as shown by anticlockwise darts *b*. By rotating shaft 41 anticlockwise, the insulator 63 is rotated anticlockwise, thus moving its switch arm 97 to open position (see dart *c*). In accordance with this movement, elbow 135 moves clockwise (see dart *d*). The opening movements of the switch arms 97 are on the order of 90°. The opening movements of the elbows 135, 136 and 138 are on the order of 45°, as determined by engagement of lug 151 with stop 163 or 165, as the case may be (see Figs. 5 and 6). This movement is sufficient to allow escape of the ends 139 of the respective switch arms 97 from the respective spring clip assemblies 137. At the same time, the clip assemblies are held in position for reentry of the beveled ends of the switch arms 97 upon reclosing movements which are opposite to those shown by said darts *a*, *b*, *c* and *d*. It will be understood that angling closing movements of the insulators 61, 63 and 65 are limited by the stops 75 and 77. The degree of the angling opening movements of the insulators 61, 63 and 65 is not critical, it being understood that suitable notches may be employed in the brackets 43 and 48 at the bottom of the pole for accepting the handles 45 in open and closed positions of the respective switches, that is, when the handles are dropped from the operating position 45' to the vertical positions shown. Fig. 10 illustrates an important feature of the invention, namely, that the side-break arrangement between the ends of rotary arms 97 and the rotary clip assemblies 137 affords ample rotary clearance between the ends of said arms during opening and closing movements, which would not be as feasible if the arm ends were swingable merely into stationary contact clips on the stationary insulator 117.

In order to provide a snap-acting horn gap to avoid an arc that might otherwise be drawn between the ends of the switch arms 97 and the spring clip assemblies 137 upon opening movements, each arm 97 is provided with a conductive bracket 171 clamped thereto. This supports a spring conductor wire 173. The wire in closed position of the switch rests upon a rigid conductor strap 175, bolted to the conductive spider 125 as shown at 177. Each strap 175 arches over its respective elbow 135, 136, 138, as the case may be, and at its end is provided with a sloping U-shaped detent and cam member 179. Thus when a switch is opened, its conductive wire 173 rides out over the strap 175 and is temporarily caught within the legs of the U-shaped member 179 as the respective opening switch arm 97 leaves the respective spring clip assembly 137. Thereafter the wire 173 is drawn out of the U-shape 179 and springingly snaps so as rapidly to open the circuit, breaking any arc that may tend to form between the strap and wire. In order to prevent vibration of the released wire 173 and possible restriking of the arc each bracket 171 is provided with a pair of rigid arms 181. Between these arms is fastened a pad of resilient material 183 such as artificial rubber, leather, canvas or the like, which receives the impact of the wire 173 as it snaps upon release from

its respective catch 179. This damps out all vibratory action of wire 173 that might otherwise occur. Upon closing movement, the wire moves up the outside slope of the U-shape 179 (riding up pad 183) and again takes up a contact position on the strap 175, as shown in Fig. 3.

In view of the above, it will be seen that the substantially equilateral triangular arrangement of rotary insulators for the switch arms 97, the stationary insulator 65 located at or near the geometric center of this triangle, and the radially arranged side-break switches provide a structure wherein interference between switch-opening elements is avoided, while at the same time all of the parts constituting each of the three individual rotary switches may be manufactured of identical parts. In this connection it will be noted that the reversibility of the cam ring 147 contributes to this interchangeability, even though it is required that two of the switches in an assembly such as shown in Figs. 2 and 10 shall open in a clockwise direction of their switch arms, whereas the other switch in such assembly opens in an anticlockwise direction of its switch arm.

If it is desired to carry out the construction as a two-way arrangement rather than the three-way arrangement shown, the parts for any one switch, as shown in Fig. 2, may be omitted, the advantages of the invention being preserved in respect to the remaining two switches. If any one switch is omitted, it is possible that the unnecessary portions of the supporting framework may be omitted, although this is not absolutely necessary. The relatively small number of parts that need to be stocked will be apparent when it is noted that the parts for each rotary assembly connected with insulator 61, 63 or 65 are the same, including arms 69 and 97, and likewise the parts that are associated with each assembly for the rotary assembly 137 are the same, including the spring arcing horn parts. In addition, all of the parts for shafts 39, 41 and 47, including the arms 55, 57 and 59, may be made the same. The rods 81 and 85 may be identical and of course all of the parts of each supporting frame at A, B and C may likewise be identical. In view of the above, it will be seen that the new arrangement provides from a relatively small number of parts a safe, reliable and compact sectionalizing air-break switch which is applicable to a large number of circuit arrangements required to be controlled.

In general, as indicated in Fig. 10, the rotations of the two rotary insulators 61 and 63 will be opposite, as determined by the adjustably positioned stops 75. While the rotation of the insulator 65 is shown as being clockwise in order to open its switch, it will be understood that this limited rotation may be reversed if desired by suitably positioning the respective stop 75. In such cases the corresponding switch arm 97 of the insulator should be set into proper position so that its beveled end will properly cooperate with the clip assembly adapted to receive it. Repositioning of the arm 97 may be accomplished by removing its holding bolt 99 (Fig. 7), turning the switch arm to proper position and reinserting the bolt.

It will be seen from Fig. 10, that one phase of the invention may be characterized as the provision of a sectionalizing switch wherein three side-break switches having duplicate parts are arranged with their rotatable insulators on the corners of an equilateral triangle having a common insulator at the geometric center of the triangle with rotations of the elements of two pairs of the switches being respectively opposite, and those of another pair of said switches being the same.

In view of the above, it will be seen that the several objects of the invention are achieved and other advantageous results attained.

As various changes could be made in the above constructions without departing from the scope of the invention, it is intended that all matter contained in the above

description or shown in the accompanying drawings shall be interpreted as illustrative and not in a limiting sense.

We claim:

- 5 1. A sectionalizing switch comprising three side-break switches, each of which has a horizontally swinging switch arm and a rotary insulator supporting said switch arm for swinging movement, and all of which have a common stationary insulator located substantially at the geometric center of an equilateral triangle having its corners at the centers of rotation of the rotary insulators, a conductive bushing affixed to the common insulator, three spring clip assemblies rotatable in the bushing and engageable and disengageable with the respective switch arms upon respective rotations of the latter, reversible stop means for the swinging switch arms, and reversible stop means for the rotatable clip assemblies, whereby each switch may be assembled from substantially identical insulator, clip assembly and switch arm parts for various directions of rotation of its side-break switches for opening and closing movements.
- 10 2. A sectionalizing switch comprising at least two vertical insulators rotatable on first and second vertical axes establishing centers of rotation, a stationary insulator having a third vertical axis establishing a point located substantially to one side of a straight line joining said centers, said point and said centers establishing angled center lines corresponding to closed-circuit operations, a stationary conductive member supported by the stationary insulator, at least one pair of first conductive elbows rotatable on vertical elbow axes in said conductive member, each vertical elbow axis being located on one of said center lines between said point and one of said centers, said elbows having swingable open-ended spring clip-forming sockets which move in a horizontal plane in paths clear of said third vertical axis, the open end of each of said sockets being directed away from said point, a second pair of conductive elbows carried by and rotatable with said rotatable insulators respectively, horizontally directed conductive switch arms having horizontal axes extending respectively from said second pair of elbows, stop means establishing a coaxial relation between each switch arm and the axis of its associated clip socket in circuit-closed position thereof on one of said center lines with a switch arm in its respective socket, and stop means for limiting opening movement for each of said first pair of elbows to a stop position wherein the swinging end of a cooperable switch arm may leave and enter the respective socket.
- 15 3. A sectionalizing switch comprising at least two vertical insulators rotatable on first and second vertical axes establishing centers of rotation, a stationary insulator having a third vertical axis establishing a point located substantially to one side of a straight line joining said centers, said point and said centers establishing angled center lines of equal lengths, a stationary conductive member supported by the stationary insulator, at least one pair of first conductive elbows rotatable on vertical elbow axes in said conductive member, each vertical elbow axis being located at the same relative position on one of said center lines between said point and one of said centers, said elbows having swingable open-ended spring clip-forming sockets of substantially equal forms which move in a horizontal plane and form extensions of substantially equal lengths from said conductive member, the open ends of said sockets being directed away from said point, a second pair of conductive elbows of substantially equal forms carried by and rotatable with said rotatable insulators respectively, horizontally directed conductive switch arms of substantially equal lengths having horizontal axes extending from said second pair of elbows, reversible stop means establishing a coaxial relation between each switch arm and the axis of its associated clip socket in circuit-closed position thereof on one of said angled center lines, and

- 75

reversible stop means for limiting opening movement for each of said first pair of elbows to a stop position wherein the swinging end of a cooperable switch arm may leave and enter the respective socket.

4. A sectionalizing switch comprising three vertical insulators rotatable on centers established by three vertical axes on the apexes of a triangle, a stationary insulator having a vertical axis establishing a location within said triangle and substantially to one side of any of the three straight lines joining two of said apexes, 5 said location and said apexes establishing three angled center lines, a stationary conductive member supported by the stationary insulator, a first set of three conductive elbows rotatable on vertical elbow axes in said conductive member, each vertical elbow axis being positioned on one of said center lines between said location and one of said centers, said elbows having swingable spring clip-forming open-ended sockets which move in a horizontal plane in paths clear of said location, the 10 open end of each of said sockets being directed away 15 from said location, a second set of three conductive 20

elbows carried by and rotatable with said rotatable insulators respectively, horizontally directed conductive switch arms having horizontal axes extending from said second set of three elbows, stop means establishing a coaxial relation between each switch arm and the axis of its associated clip socket in circuit-closed position thereof on one of said angled center lines, and stop means for limiting opening movement for each of said first set of three elbows to a stop position wherein the swinging end of a cooperable switch arm may leave and enter the respective socket.

5. A sectionalizing switch according to claim 4, wherein said triangle is equilateral and said location is substantially at its geometric center.
